Primary Examiner — Kimberly Barnes(74) *Attorney, Agent, or Firm* — Patentfile, LLC; Bradley C. Fach(57) **CLAIM**

The ornamental design for a removable batter protection device, as shown and described.

DESCRIPTION

FIG. 1 is a perspective view of a removable batter protection device showing my new design being worn by a baseball or softball batter;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in FIG. 1 depicting a batter represent environmental subject matter that forms no part of the claimed design. The broken lines in the drawings depicting padding, lines of stitching, and the hook and loop attachment areas represent portions of the removable batter protection device that form no part of the claimed design.
